SUCTION CLEANER

Joseph H. Nuffer, Toledo, Ohio, and Lynn H. Latta, Deerfield, Ill., assignors to Air-Way Electric Appliance Corporation, Toledo, Ohio, a corporation of Delaware

Application October 1, 1942, Serial No. 460,362

17 Claims. (Cl. 15—16)

This application relates to suction cleaners of the type wherein the filtering and dust collecting unit is located between the cleaning tool and the suction unit, within an imperforate housing from which the air is evacuated by the suction unit so as to cause a dust laden stream of air to be drawn into the collecting receptacle from the cleaning tool. The primary object of the invention is to embody this type of arrangement in a relatively economical cleaning implement almost wholly contained within a slender, elongated, streamlined body, symmetrical with reference to the longitudinal axis thereof. In particular, the invention aims to achieve, in an implement of such form, maximum cleaning efficiency coupled with minimum diameter of the body of the implement.

A further object of the invention is to provide a suction cleaner wherein the highly desirable dust collector receptacle and housing arrangement illustrated in the application of Dewey M. Dow et al. Serial Number 337,836, filed May 29, 1940, and issued April 13, 1943, as U. S. Patent 2,316,674, characterized particularly by the ease with which the receptacle may be removed from and replaced in the housing, is incorporated in an implement having the slender, streamlined and symmetrical form above referred to. More specifically, the invention aims, in this respect, to provide a suction cleaner incorporating an elongated, slender, streamlined body which comprises two sections, separable from each other along a plane transverse to the longitudinal axis of the body, one of the sections incorporating the dust collecting and air filtering mechanism and the other section incorporating the suction unit, access to the collecting receptacle for the purpose of removing and replacing the same being obtained by "breaking" the body along this transverse plane, and the securing of the receptacle in its housing and the sealing of the mouth thereof to the nozzle which delivers the dust laden air stream, being accomplished merely by bringing the sections together after the receptacle has been inserted in the housing section.

Another object of the invention is to provide a suction cleaner which has its suction unit located in the lower region thereof and its dust collecting and filtering unit located in the upper region thereof so as to concentrate the weight in the lower region, and, in addition, embodies an arrangement wherein the connection between the cleaning tool and the body of the cleaner is in the lower portion of the body, the dust laden

air stream is passed upwardly through the lower portion of the body so as to reach the collecting and filtering unit and the filtered air is thence drawn back into the lower region of the body by the suction unit, and wherein the receptacle mouth is centrally disposed, the passage for the dust laden air stream is direct, and the body is symmetrical in cross section and of minimum diameter coupled with maximum cleaning efficiency.

Other and further objects of the invention will occur to those skilled in the arts to which this invention pertains as the description proceeds which, taken in connection with the accompanying drawings, sets forth a preferred embodiment and selected modifications are not to be construed as limitations of the invention but only as illustrative thereof and any and all modifications, alterations and variations of structure coming within the spirit and scope of the appended claims which limit and define the instant invention are deemed to be included herein.

In the drawings:

Fig. 1 is an inverted plan view of a suction cleaner embodying the invention;

Fig. 2 is a side elevation of the same, partially in section;

Fig. 3 is an end view of the filtering section of the cleaner;

Fig. 4 is an end view of the motor fan section of the cleaner;

Fig. 5 is a detail sectional view of a portion of the cleaner;

Fig. 6 is a side elevation, partially in section, of a modified form of the invention;

Fig. 7 is a side elevation, partially in section, of a vertical cannister type cleaner embodying the invention;

Fig. 8 is an inverted plan view of the cleaner shown in Fig. 7; and

Fig. 9 is a partial end view of the filtering section of the cleaner shown in Fig. 7.

As an example of one form in which our invention may be embodied, we have shown in Fig. 1 a suction cleaner embodying a cleaning tool indicated generally at A, a body indicated generally at B and a handle indicated generally at C. The body B is elongated, symmetrical, of minimum diameter coupled with maximum cleaning efficiency, and, in general, streamlined so as to be easy to handle, easy to store in a closet, and pleasing in appearance. It is contemplated that the invention, in this form, will be embodied in a relatively small and inexpensive cleaner

to be used for doing supplementary cleaning, i. e., the cleaning of a small area as contrasted to a complete cleaning of an entire living quarters. At present it is customary to use a light carpet sweeper for supplementary cleaning in cases where the amount of cleaning to be done does not justify the trouble of getting out the usual suction cleaner. Our invention aims to provide, in the implement shown in Fig. 1, a suction cleaner which is comparable to a carpet sweeper in lightness, ease of manipulation, and the readiness with which it can be removed from and stored in a closet.

The body B is formed in two sections, indicated generally at 10 and 12. The section 10 incorporates the suction unit which comprises a multiple stage fan, indicated generally at 14, a motor for driving the same, indicated generally at 16, and a casing comprising a lower section or fan casing 20 and upper section or motor casing 22. Joined to the housing 18 is the cleaning tool A which, in form of the invention shown in Fig. 1, may be formed integrally with the lower section 20 of the casing 18.

The section 12 of the cleaner body comprises a tubular housing 26 closed at its upper end by a cap 28 in which is secured the cleaner handle 30. Within the housing 6, and spaced from the inner surface thereof is an air pervious sleeve 32, preferably of rigid sheet material. Within the sleeve 32 is supported the air porous dust receptacle 34 which is in the form of an elongated bag having one end closed and having at its other end an inlet end member 36 which is clamped between the body sections 10 and 12 when the latter are joined together as shown in Fig. 2. The end member 36 has an inlet 38 through which the dust laden air stream is injected into the receptacle 34.

Dust laden air received by the cleaning tool A is delivered to the receptacle 34 through a passage extending axially through the center of the fan 14 and the motor 16. In the form of the invention shown in Fig. 2, this passage is formed by a continuous suction tube 40 the upper end of which constitutes a nozzle 42 adapted to extend into the receptacle through the inlet 38. The tube 40 is fixedly mounted in the casing 18, the lower end being fixed in the neck 44 joining the cleaning tool A to the casing section 20, and the upper end being fixed in a boss 46 in a spider 48 which forms the upper end portion of the casing section 22. By thus extending the suction tube through the center of the fan and motor, it is possible to utilize the full cross sectional area of the casing 18 for accommodating a fan of maximum diameter and therefore of maximum suction capacity. At the same time, it is possible to maintain symmetry in the cross sectional shape of the casing, the suction tube being co-axial with all other parts. A further advantage arises from the fact that in passing the suction tube through the center of the fan and motor it is possible to make the suction passage perfectly straight, eliminating bends that would be necessary if the passage were brought from the floor tool around the exterior of the fan and thence bent inwardly to reach the inlet of the collecting receptacle. Eliminating the bends in the passage minimizes the danger of clogging, and reduces its length to a minimum. Both of these factors increase the efficiency of the cleaner by reducing the resistance to the passage of the dust laden air stream.

The motor 16 comprises a field 24 which is

mounted in the casing section 22 between a shoulder 50 therein and a collar 52. The armature 54 of the motor is mounted upon a hollow shaft 56 telescoped upon the suction tube 42 and journaled on bearings 58 and 60, the former interposed between the tube 42 and an enlarged collar 62 on the lower end of the tubular shaft 56, and the latter being mounted between the upper end of the shaft 56 and a boss 64 on the spider 48.

The fan 14 includes the impellers 66 and 68 respectively, operating in fan chambers formed between the lower end of the casing section 20 and a partition 74 and between a partition 76 and a partition 78, respectively. The impellers 66 and 68 are secured in spaced relationship on the shaft 56 between the enlarged collar 62, spacing sleeves 86, and the armature 54.

Attached to the lower end of the filter housing tube 26 is a spider 94 in the form of a ring the inner periphery of which defines the mouth through which the receptacle 34 is inserted into the housing 26. The spider 94 is connected by a hinge 96 to the casing section 22 and carries a latch 98 adapted to latch the two sections of the cleaner body together. The inlet end of the receptacle 34 has a peripheral flange 102 which is adapted to be engaged between the end wall 48 of the casing section 22 and the spider 94 when the body sections 10 and 12 are latched together. The flange 102 is connected to the central portion to the end member 36 by an offset wall portion 104, to which is stitched the porous wall portion of the receptacle 34. This receptacle construction is illustrated more clearly in the patent to D. M. Dow et al., 2,316,674, above referred to.

A sealing gasket 100 of soft rubber encircles the nozzle 42 and abuts the end of the boss 46. The ring 100 is adapted to engage the end member 36 of the receptacle when the body sections 10 and 12 are latched together, so as to securely seal the nozzle 42 to the inlet 38 of the receptacle. The body sections 10 and 12 are simultaneously sealed by a sealing ring 106 mounted in a channel 108 in the spider 94 and engaging the end wall 48 of the casing section 22.

The air exhausted from the receptacle 34 passes through the supporting sleeve 32 into the annular space 112 defined between the sleeve 32 and the housing 26, thence passes through an annular series of apertures 114 in the spider 94, thence through a corresponding annular series of apertures 116 in the end wall 48 of the motor casing, thence through the motor 16 (between the armature 54 and the field 24), and thence through the fan inlet 92 into the upper fan chamber, thence through the ports 80 and the inlet 82 into the lower fan chamber and then through the outlet apertures 84 in the casing 20, to the atmosphere. Thus the suction from the fan is applied to the housing 26 through the motor housing 22 and across the dividing plane between the sections 10 and 12. The gasket 106 seals the two sections together against the loss of suction across this dividing plane. The gasket 100, on the other hand, seals the nozzle 42 to the receptacle 34 so that dust will not escape into the space between the receptacle and the end wall 48. The air in passing through the motor 16, cools the same. Not until after the air has passed through the motor is it heated by compression in the fan 14, and the heat thus developed is immediately dissipated into the atmosphere by the discharge of the air through

the outlet apertures 84. The passage of air through the center of the motor also helps to dissipate heat developed in the motor.

The supporting sleeve 32 is received within the end cap 28 at its upper end and abuts against the inner side of the spider 94 at its lower end.

Current is delivered to the motor 16 through brushes 120 and a motor cord 122 which extends from the brushes 120, through the hinge 96, then through the spider 94 and the space 112 between the sleeve 32 and the housing 26, and thence through the hollow handle 30 to a switch 124 mounted in the handle 30. From the switch 124 a service cord 126 extends through the end of the handle.

The receptacle 34, when filled, may be quickly made accessible for removal by turning the cleaner upside down, releasing the latch 98, and hingeing the section 10 back upon the section 12 so as to uncover the mouth of the filter housing 26. The receptacle is then simply lifted out of the housing 26 and disposed of and a fresh receptacle is inserted in the housing, the flange 46 thereof serving to accurately center the end member in the housing. The section 10 is then returned to its normal position in alignment with the section 12, causing the nozzle 42 to enter the inlet 38 of the receptacle end member 36. At the same time, the end wall 48 of the section 10 will engage the flange 102 of the end member 36, securely clamping the receptacle in place, and the sealing ring 106 will engage the end member 36 to seal the nozzle 42 in the inlet 38.

In the form of the invention shown in Fig. 6, the suction passage from the floor tool 24 to the nozzle 42a is partially formed by the rotating shaft 56a on which the armature 54a and the impellers 66a and 68a of the fan 14a are directly mounted. The shaft 56a is mounted in bearings 58a and 60a respectively, the bearing 58a being mounted in a cup 130 on a lower fan case wall 132, and the bearing 60a being mounted in a cup 134 on the upper end wall 48a of the motor housing 22a. The bearings 58a and 60a are locked upon the shaft 56a by nuts 135 and 136 respectively, and is sealed with reference to the fan and motor casing by means of bellows seals 138 and 140 engaged between the nuts 134, 136 and the cupped portions 130, 134.

The impellers 66a and 68a and the armature 54a are spaced apart on the shaft 56a by means of spacing sleeves 86a.

The wall member 132, together with partition numbers 74a, 76a and 78a, which are provided with suitable peripheral flanges by means of which they are supported within the casing sections 20a and 22a and properly spaced apart, form the upper and lower fan chambers, the former having an inlet 92a and an outlet 80a, and the latter having an inlet 82a and an outlet 84a. The field 48a of the motor 16a is engaged between a shoulder 50a in the casing section 22a and a peripheral flange of the partition wall 78a and thus secured in assembly when the casing sections 20a and 22a are secured together through the medium of the flange 90a.

The nozzle 42a is of soft rubber and in the form of a valve adapted to open under the effect of suction to permit the passage of a dirt laden air stream therethrough, and to close when the suction stops, so as to prevent the collected dirt from dropping back into the suction passage. The nozzle is formed integrally with the sealing ring 106a and is mounted on a neck 142 formed

on the cup 134 and registering with the upper end of the motor shaft 56a.

The casing 20a is provided with an outlet 90 to which a flexible hose may be attached when it is desired to use the cleaner for blowing operations. The lower end of the cup 130 is abutted against the upper end of the suction tube 70 so as to seal off the latter from the chamber 12 through which the air passes from the fan casing outlet 84a to the blower outlet 90.

The dust collecting mechanism is the same as that shown in Fig. 2, and the same reference characters have been used to designate the same, with the exception that the exponent a has been added.

In Fig. 7 we have illustrated the invention as embodied in a cleaner of the upright cannister type, wherein the dust collecting unit 12b is superimposed upon the motor-fan unit 10b. The motor fan unit is mounted upon a base 150 which in turn is mounted upon casters 152 swiveled to the legs 154 thereof. The motor 16b and fan 14b are mounted within a skirt 156 which is mounted on the base 150. The motor 16b is encased within a motor casing 159 which is suspended within the skirt 156 through the medium of a resilient mounting 158. A fan casing 160 is secured to the lower end of the motor casing 159 and the bottom thereof is provided with an open collar 162 which communicates with one end of a suction conduit 164 formed in the base 150, being sealed therein by a grommet 166 of soft rubber or the like. To the upper end wall 168 of the motor casing 159 is secured a plate 170 which forms a seat for the flange 102b of the receptacle end member 36b. The seating of the flange 102b against the plate 170, under the pressure of the dust collector housing assembly, is yieldingly accommodated by the grommet 166 and the yieldable mounting 158, the latter serving to cushion vibrations originating in the motor, fan assembly.

The hollow shaft 56b of the motor-fan assembly encircles the stationary tube 40b the lower end of which is mounted in the collar 162 and the upper end of which is piloted in the outwardly cupped central portion 172 of the plate 170. Between the cupped portion 172 and the top wall 168 is mounted a bearing 60b in which the upper end of the shaft 56b is journaled. In a partition wall 175 separating the motor casing 159 from the fan casing 160, is mounted a bearing 58b in which the intermediate portion of the shaft 56b is journaled.

Upon the upper end of the suction tube 40b is mounted a resilient valve nozzle 42b having a sealing ring 106b at the base thereof.

The construction of the motor 16b and the fan 14b is substantially the same as that of the forms previously described, and the same reference characters (modified by the addition of the exponent b,) have been used to designate the parts thereof.

The suction conduit 164 terminates, near one edge of the base 150, in an inlet 174 to which suction hose may be applied. It is contemplated that the connection between a suction hose and the conduit 164 may be such that the cannister may be pulled about on the casters 152 while the operator applies a cleaning tool, at the other end of the suction hose, to the surface being cleaned. The principal advantage of the invention as embodied in this type of cleaner is the low level at which it permits the pull from the hose to be applied to the cannister, so as to make it possible

to pull the cannister about without toppling it over under the pull of the hose, and this constitutes one of the objects of the invention.

The filtering and dust collecting unit includes the filtering receptacle 34b which is receivable within a perforated supporting sleeve 32b the upper end of which is received within the rim of the dome member 28b closing the upper end of the housing 26b. The lower end of the sleeve 32b is piloted between a plurality of lugs 176 projecting inwardly from the collar 94b in which the lower end of the housing tube 26b is secured. The sleeve 32b has an outwardly turned flange 178 which is supported against the under sides of the lugs 176 and forms an annular clamping member for engaging the upper side of the flange 102b of the end member 36b and clamping the same against the plate 170.

The construction just described constitutes an improvement over the filtering mechanism shown in Fig. 1, in that the lower end of the bag supporting sleeve is made to function as the upper clamping member, thus simplifying the construction of the collar 94b and facilitating the assembly of the parts of the filtering section.

The collar 94b is hinged at 96b to the skirt 156 and carries a latch 98b adapted to engage a hook on the skirt 156. A gasket 108b, mounted in the collar 94b, is adapted to engage an in-turned flange 180 on the upper end of the skirt 156 so as to seal the filter housing 26b to the chamber 182 formed above the resilient mounting 58 within the skirt 156. The chamber 182 communicates with the interior of the motor housing 159 through an inlet 184 in the latter, which inlet is located above the field 24b so that the air exhausted from the filter housing 26b will be drawn through the motor before reaching the fan 14b. The air passes from the motor housing into the fan housing 160 through apertures 186 in the partition wall 175. From the fan casing 160 the air passes through exhaust apertures 188 into the chamber 172b formed in the skirt 156 between the base 150 and mounting 158, and thence passes through an outlet 90b in the base 150. The outlet 90b is adapted to have a flexible hose connected thereto for the purpose of utilizing blowing tools.

In the operation of the cleaner, a dust laden air stream coming from a cleaning tool will pass through the suction conduit 164 into the suction tube 40b and will thence be delivered upwardly through the nozzle 42b into the receptacle 34b. The air will be drawn through the wall of the receptacle 34b and thence downwardly through the space 194 between the sleeve 32b and the housing 26b thence downwardly between the lugs 176 and through the annular space between the flange 172 and the rim of the collar 94b, thence into the chamber 182.

When the receptacle 34b is filled, the latch 98b is released and the filter housing 26b is tilted, about the hinge 96b, to a position where its normally upper end is resting against the floor. The receptacle is then changed in the manner previously described.

The upper end of the filter housing is provided with a suitable handle 192 to facilitate the carrying of the cannister from place to place and the manipulation of the filter housing during the changing of filter receptacles. This handle may be formed integrally with the dome member 28b as shown, or may be separate and secured to any part of the upper region of the filter housing.

We claim as our invention:

1. In a vacuum cleaner, an air filtering and dust collecting receptacle, a housing receiving said receptacle, a suction fan for evacuating the air from said housing, a cleaning tool, a duct for conveying dust laden air from said cleaning tool to said receptacle, said duct passing axially through said fan, and a casing for said fan associated with said housing and providing a passage affording communication between an exterior portion of said receptacle and the inlet of said fan.
2. In a vacuum cleaner, an air filtering and dust collecting receptacle, a housing enclosing said receptacle, a suction fan for evacuating the air from said housing, a motor for driving said fan, a cleaning tool, a duct for conveying dust laden air from said cleaning tool to said receptacle, said duct passing through said motor and through said fan, and a casing for said fan associated with said housing and providing a passage affording communication between an exterior portion of said receptacle and the inlet of said fan.
3. In a vacuum cleaner, an elongated housing adapted to enclose an air filtering and dust collecting receptacle having a mouth disposed at one end of the housing, and a suction unit including a casing associated with said housing at said one end thereof and coaxially therewith, a suction fan in said casing, said casing providing an annular passage communicating at one end with said one end of the housing exteriorly of said receptacle and at its other end with the inlet of said fan whereby said fan may evacuate air from said housing and receptacle, and a duct for conveying dust-laden air to said receptacle mouth, said duct extending along the common axis of said housing and casing and passing through the center of said fan.
4. In a vacuum cleaner, a dust collecting and air filtering receptacle having an inlet end provided with a mouth, a housing enclosing said receptacle and having at one end an air outlet disposed about the periphery of said inlet end of the receptacle and a suction unit comprising a casing associated with said one end of the housing, a suction fan in said casing adapted to draw air from said housing through said outlet and through said casing, and a duct for conveying dust laden air to said receptacle mouth, said duct passing through the center of said fan.
5. A vacuum cleaner as defined in the preceding claim, including an electric motor coaxial with and in driving relation to said fan, said motor being disposed in the air stream passing through said casing from said housing to said fan and said duct passing axially through said motor.
6. In a vacuum cleaner, a suction fan, a cleaning tool, a filtering receptacle, a duct for conveying dust laden air from said cleaning tool to said filtering receptacle, said duct passing axially through said fan, said fan having an annular inlet encircling said duct, through which said fan is adapted to draw filtered air from said receptacle, and a housing for said receptacle having an air outlet communicating with the inlet of the fan.
7. In a vacuum cleaner, a cleaning tool, a filtering receptacle, a suction fan, an electric motor coaxial with and in driving relation to said fan, a duct for conveying dust laden air from said cleaning tool to said filtering receptacle, said duct passing axially through said fan and motor, said fan having an annular inlet encircling said duct

through which said fan is adapted to draw filtered air from said receptacle, and a housing for said receptacle having an air outlet communicating with the inlet of the fan.

8. In a vacuum cleaner, a suction fan, an electric motor coaxial with and in driving relation to said fan, a duct for conveying dust laden air to a filtering receptacle, said duct passing axially through said fan and motor, said fan having an annular inlet encircling said duct, through which said fan is adapted to draw filtered air from said receptacle, and a casing enclosing said motor and fan and forming an annular passage for directing the filtered air through the motor for cooling the same, and thence into the fan.

9. In a vacuum cleaner, a casing having at one end a cleaning tool and adapted to communicate at its other end with dust collecting and air filtering means, a suction fan in said casing for inducing a flow of air therethrough to and from said dust collecting and filtering means, a duct passing axially through said fan, said duct at one end communicating with said tool for applying suction thereto and at its other end discharging to said collecting and filtering means and an annular passage defined between said duct and said casing for conveying the air stream away from said collecting and filtering means, said fan having an annular inlet encircling said duct and communicating with said annular passage.

10. In a vacuum cleaner, a casing having at one end a connection to a cleaning tool and adapted to communicate at its other end with a housing enclosing a dust collecting and air filtering receptacle having at the open end of said housing an inlet mouth, a suction fan in said casing adapted to withdraw filtered air from said open end of the housing, a motor for driving said fan, including an armature, a tubular shaft on which both said armature and said fan are mounted, and a tube passing axially through said shaft for conveying dust laden air from said cleaning tool connection to said receptacle, said tube terminating in a nozzle adapted to make connection with said mouth, said shaft being mounted for rotation about said tube.

11. A vacuum cleaner as defined in the preceding claim, wherein said housing is movable from a normal position in communication with said casing, with said duct in communication with said receptacle mouth, to a position wherein said one end of the housing is uncovered to permit the withdrawal of said receptacle and wherein said duct is separated from said mouth.

12. A vacuum cleaner as defined in the second preceding claim, wherein said receptacle has at said inlet end a flange extending outwardly from the body thereof, and wherein said casing is adapted to clamp said flange against said one end of the housing.

13. In a vacuum cleaner, an elongated collector housing having at one end a handle and at its other end an annular outlet for filtered air, a filtering receptacle receivable in said housing and having an inlet end adapted to lie within the inner circumference of said outlet, said inlet end having a mouth, and a suction unit including a casing normally aligned with said housing, with one end thereof communicating with said outlet, a cleaning tool on the other end of said casing, a fan within said casing adapted to draw air from said housing through said outlet and through said casing, and a duct for conveying dust laden air from said tool to said mouth, said duct passing through the center of said fan.

14. A vacuum cleaner as defined in the preceding claim, wherein said duct extends in a straight line along the common axis of said housing and casing and through the center of said fan.

15. A vacuum cleaner as defined in the second preceding claim, wherein said receptacle has at said inlet end a flange extending outwardly from the body thereof, and wherein said casing and housing are relatively movable from normal positions in communication with each other, with said duct in communication with said mouth, and with said flange clamped between the adjacent ends of said casing and said housing, to positions wherein said other end of the housing is uncovered to permit the removal of said receptacle therefrom and wherein said duct is withdrawn from said mouth.

16. In a vacuum cleaner, a collector housing having at one end an annular outlet for filtered air, a filtering receptacle receivable in said housing and having an inlet end adapted to lie within the inner circumference of said outlet, said inlet end having a mouth; a suction unit including a casing normally aligned with said housing, with one end thereof communicating with said outlet, and a fan within said casing; a cleaning tool; and means for conveying dust laden air from said cleaning tool to said filtering receptacle mouth, said means comprising a duct passing through the center of said fan.

17. A vacuum cleaner as defined in claim 16, wherein said receptacle has at said inlet end a flange extending outwardly from the body thereof, and wherein said casing and housing are relatively movable from normal positions in communication with each other, with said duct in communication with said mouth, and with said flange clamped between the adjacent ends of said casing and said housing, to positions wherein said other end of the housing is uncovered to permit the removal of said receptacle therefrom and wherein said duct is withdrawn from said mouth.
